UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

AUTOMATIC SHOE-MACHINE.

1,310,463.

Specification of Letters Patent. Patented July 22, 1919.

Application filed August 1, 1912 Serial No. 712,702. Renewed March 27, 1917. Serial No. 157,844.

To all whom it may concern:

Be it known that I, ERASTUS E. WINKLEY, a citizen of the United States, residing at Lynn, in the county of Essex and State of Massachusetts, have invented certain new and useful Improvements in Automatic Shoe-Machines; and I do hereby declare the following to be a full, clear, and exact description of the invention, such as will enable others skilled in the art to which it appertains to make and use the same.

The invention relates to automatic or semi-automatic machines in which the requisite relative movements between the work and the means for operating thereon to bring them into proper relation at the point of operation are automatically controlled and effected.

In various shoe machines it is necessary, in order to bring the operating means and shoe into or to maintain them in proper relation at the operating point, to relatively tip them in one or in two directions. It is the primary object of the present invention to provide novel and improved mechanism for accurately determining and effecting the relative tipping movements requisite for securing these results. To this end the invention contemplates determining the tipping movements requisite for bringing the work and operating means into proper relation by feelers arranged to engage the surface of the shoe or other work adjacent to the point of operation, and connected to control the action of the tipping mechanisms. The preferred form of the invention is especially designed for use in a machine for lasting shoes, the parts of which have been assembled on a last, and in the drawings the invention is shown embodied in such a machine.

In addition to the features outlined above, the invention includes further features of construction and combinations of parts hereinafter described and set forth in the claims, the advantages of which will be understood by those skilled in the art from the following detailed description of the machine embodying the invention in its preferred form.

The various features of the present invention will be best understood from an

inspection of the accompanying drawings illustrating the preferred embodiment of the invention, in which,

Figure 1 is a right side elevation of the machine;

Figs. 2 and 3 taken together are an enlarged right side elevation, a portion of the lasting head, jack, and supporting frame being broken away to show underlying parts;

Fig. 4 is a front elevation of the parts illustrated in Fig. 2;

Fig. 27 is a detail, in right side elevation, of the feeler devices; and

15 Fig. 28 is a detail, in front elevation, of the parts illustrated in Fig. 27.

The embodiment of the invention illustrated in the drawings is provided with a stationary lasting head of the consolidated hand method or "nigger head" type, the general construction of which is fully described and illustrated in the United States Patents to S. W. Ladd and R. F. McFeely, 584,744, June 15, 1897; S. W. Ladd, 597,321, 20 Jan. 11, 1898; and J. Cavanagh, Jr., 873,018, Dec. 10, 1907. The lasting head carries automatically operating pincers 1, a sole rest 2, a tacker 3, an edge guide 4, a plaiting mechanism actuating lever 5, and a wire 25 reel spring tension releasing rod 6. The lasting instrumentalities carried by the lasting head are operated in the same manner as the corresponding lasting instrumentalities in the patents referred to, and therefore, 30 they need not be described in detail herein as reference may be had to said patents. Certain improvements, however, have been made in the mechanism for actuating certain 35 of the devices carried by the lasting head in adapting them to the operation of the present machine consisting principally in an improvement in the mechanism for operating the wire reel spring tension releasing rod 6 by which the rod is operated automatically to release the tension of the wire 40 reel spring.

The plaiting mechanism actuating lever 5 is connected to one end of a horizontal rod 8 (Fig. 3) the rear end of which is yoked 45 to embrace the free end of an arm 9 projecting from the upper end of a vertical rock shaft 10 journaled in lugs 11 projecting from the machine frame. The lower end of the rock shaft 10 (Fig. 2) is connected to 50 the rear end of a horizontal rod 12, the forward end of which is connected to an arm projecting from a sleeve 13 rotatably mounted on a vertical pin 14 carried by a bracket 15 bolted to the machine frame. The sleeve 55 13 carries a segment 15^a which meshes with a similar segment (Fig. 1) formed on the knee lever 7.

The wire reel spring tension releasing rod 6 (Fig. 3) is connected at its rear end to 60 the lower end of a lever 16 centrally pivoted

to one of the lasting head supporting brackets. The upper end of the lever 16 is connected by a horizontal rod 17 to an arm 18 (Fig. 5) pivotally mounted on a rock shaft 19 journaled in the machine frame. A second arm 20 projecting from the rock shaft carries a roll 305 engaged by a peripheral groove formed in a cam 21 secured to the driving shaft 22 for the lasting instrumentalities.

The last having assembled thereon the insole and upper and parts within it, hereinafter for brevity termed the "shoe", is mounted upon a jack 23 of the well known saddle and spindle type. This jack is secured to the upper end of a vertical spindle 24 (Figs. 1 and 17) which is splined in an elongated hub 25, mounted to rotate freely in a frame 26, but constrained from longitudinal movement therein by a pair of collars 27 secured to the hub. The frame 26 is pivotally mounted on a hollow vertical rod 28 carried by a second frame 29, the hubs of which are pivotally mounted on a vertical rod 30 which is pinned to a jack frame 31. Through the connections described the jack is rotatable and universally movable in a plane to permit the operative to present different portions of the margin of the upper to the pincers. The jack is thrust yieldingly upward to maintain the insole in contact with the sole rest 2 by a spring 32 arranged within the hollow rod 28. One end of the spring is secured to an eye bolt 33 attached to a plug 34 fitted to the bottom of the hollow rod 28, and the other end of the spring is secured to a horizontal pin 35 arranged to extend through opposed vertical slots 36 in the rod 28 and connected to a collar 37 slidably mounted on the rod. A flange on the collar 37 engages the forked end of a lever 38 centrally pivoted on a brace 39 on the frame 26. The other end of the lever is also forked to engage a flange formed on a collar 40 slidably mounted on the hub 25 and connected through a pin 41, arranged to slide through opposed vertical slots 42 in the hub, with the spindle 24.

As is well known to those skilled in the art, the pull of the pincers in stretching the upper over the last is called the "updraw". In practice the best results are produced when the updraw of the pincers is perpendicular to the plane of the insole at the point of operation. In the operation of the commercial consolidated hand method lasting machine it is customary for the operative to tip the shoe longitudinally or laterally, or both longitudinally and laterally to maintain the plane of the insole adjacent the portion of the margin of the upper being operated upon by the lasting instrumentalities substantially perpendicular to the line of pull of the pincers in their updraw movement. To properly tip the shoe

70

130

- in the manner described requires considerable skill on the part of the operative. In the illustrated embodiment of the invention after the operative presents a pre-selected portion of the margin of the upper to the pincers the shoe is automatically tipped by rocking it to the right or left, that is, laterally, or tilting it to the front or rear, that is, longitudinally, as the occasion demands
- 5 to bring the plane of the insole adjacent the pre-selected portion of the upper perpendicular to the updraw movement of the pincers. The operative is thus relieved of the duty of tipping the shoe.
- 10 To permit the shoe to tip or tilt to the front or rear the jack frame 31 rises vertically from a carriage 43 (Figs. 1 and 17) which is provided with a series of rolls 44 to permit the carriage to slide on rails 45 formed in the opposite walls 46 and 47 of a supporting frame 48 (Figs. 1 to 4). The rails 45 extend in such an arc that a movement of the carriage 43 on the rails tilts the shoe mounted on the jack to the front or rear about the point of operation of the pincers.
- 15 To permit the shoe to tip or rock to the right or left the opposite walls 46 and 47 of the supporting frame 48 have each two upper arms (Fig. 3) of channel form (Fig. 5). The front arms of the walls 46 and 47 are connected by a hub 49 secured to the forward end of a rock shaft 50 journaled in the machine frame. The rear arms of the walls 46 and 47 are also connected by a hub 51 secured near the rear end of the rock shaft 50. The axis of this shaft passes through the point of operation of the pincers so that the shoe may be rocked to the right or left about the point of operation of the pincers by rocking the shaft 50.
- 20 In order to tilt the shoe automatically to the front or rear the carriage 43 is provided with a depending lug 52 (Fig. 1) to which is pivotally connected one end of a link 53 the other end of which is pivoted to an arm 54, in turn pivotally mounted on the supporting frame 48. Intermediate its ends the arm 54 is connected by a link 55 (Fig. 3) to an arm 56 depending from a sleeve 57 (Fig. 5) mounted on a rod 58 carried by the arms 46 and 47. Projecting upwardly from the sleeve 57 are two arms 59, each provided with rolls 60 which are engaged by a groove 61 (Figs. 3 and 5) formed in a collar 62 loosely mounted on the rock shaft 50. The upper surface of the collar 62 is formed as a rack 63 which meshes with a segment 64 (Figs. 3 and 5) formed on an arm projecting from a rock shaft 65 journaled in hubs 66 rising from the machine frame. The segment 64 is provided with a pair of flanges 67 which embrace the rack 63 and thus prevent the collar 62 from rocking with the shaft 50. The rock shaft
- 65 is provided at one end (Figs. 3 and 5) with a walking beam 68 the opposite ends of which are connected by a pair of rods 69 to a second walking beam 70 (Fig. 2) carried by a rock shaft 71, one end of which is journaled in a hub 72 formed in the machine frame (Fig. 4), and the other end of which is journaled in a bracket 73 bolted to the frame. The rock shaft 71 carries a segment 74 which meshes with a segment 75 formed on a bell crank lever 76 pivoted on a horizontal rod 77 journaled in the machine frame.
- 70 The actuating mechanism for rocking the bell crank lever 76 to tilt the shoe to the front or rear of the machine through the connections described comprises a continuously rotating drum 78 (Figs. 1, 2, 4 and 6), the periphery of which is engaged by one or more rolls 79 (Figs. 2 and 26). The drum 78 is keyed to a horizontal shaft 78^a which is continuously rotated, during the operation of the machine, from the main driving shaft 79^b provided with fast and loose pulleys 79^c, through the gears 79^d. In the construction shown there are two rolls which are connected to operate in unison, a plurality of rolls being used to give additional power to the actuating mechanism. The rolls are supported in a carriage 80 (Figs. 2, 7 and 8) which is mounted so that it may move longitudinally of the drum 78 and the rolls are so mounted that they may be turned to vary the angle of the rolls with relation to the direction of travel of the surface of the drum. So long as the axes of the rolls are parallel to the axis of the drum there will be no longitudinal movement of the carriage 80. If the rolls are turned in either direction so that their axes are at an angle to the axis of the drum then the rolls will tend to travel longitudinally of the drum and will move the carriage 80 in one direction or the other according to the direction in which the rolls are turned, and the rate of movement in either direction will depend upon the extent of the angular movement of the rolls. The travel of the rolls and carriage will cease as soon as the rolls are returned to a position in which their axes are parallel to the axis of the drum. To permit the carriage 80 to move longitudinally of the drum it is provided with an upper and lower series of sets of anti-friction rolls 81, there being three rolls in each set (Figs. 2, 7 and 8). The upper sets of three rolls embrace a flange 82 formed on an independent frame 83 bolted to the machine frame. The lower sets of rolls embrace a flange 84 formed on the frame 83. The flanges 82 and 84 thus form rails for the carriage to slide upon. The sliding movement of the carriage is transmitted to the bell crank lever 76 to tilt the shoe to the front or rear according to the direction of move-
- 75 80 85 90 95 100 105 110 115 120 125 130

ment of the carriage through the connections described by a rack 85 secured to a bracket formed on the carriage 80 and meshed with a segment 86 formed on the vertical arm of 5 the bell crank lever 76.

Referring now to Figs. 24, 25 and 26, each roll 79 is clamped between a pair of plates 87 which are secured to a shaft journaled in boxes 88 slidably mounted in a roll carrier 89 which is supported by the carriage 80. Each box 88 is provided with a pin 90 which is surrounded by a coiled spring 91 arranged within a chamber 92 in the roll carrier and interposed between the box 88 and a spring 15 retainer 93 carried on the end of a bolt 94 threaded in the roll carrier. By manipulating the bolts 94 the pressure of the frictional engagement of the rolls 79 and drums 78 may be varied as desired. The roll carrier 20 89 is pinned to a shaft 95 which is journaled in a bridge 96 formed on the carriage 80. The projecting end of the shaft 95 is pinned to a bell crank lever or tiller 97, the horizontal arm of which is provided at its free 25 end with a roll 98. This roll engages a groove 99 formed in a cam plate 100 (Figs. 7 and 8), provided near its ends with bosses 101 which are secured to vertical rods 102 mounted to slide in bosses 103 formed on the 30 frame 83. The vertical arms of the bell crank levers 97 are connected by a sectional rod 104, the sections being connected by a turnbuckle 105. Through the connections described it will be seen that when the cam 35 plate 100 is raised or lowered, the shafts 95 are turned to vary the angle of the rolls with relation to the drum, and thus cause a longitudinal movement of the carriage 80. To prevent binding of the roll carriers as they 40 are turned in the carriage 80 each carrier is arranged to turn on a ball bearing 106 interposed between the carrier and the carriage.

The direction of the tilting movement of the shoe either to the front or rear and the 45 extent thereof under the influence of the actuating mechanism described is determined by a feeler 107 arranged to engage the insole of the assembled shoe. This feeler is formed on the end of the horizontal arm of 50 a bell crank lever 108 pivotally mounted upon a horizontal stud 109 carried by the lasting head. The vertical arm of the bell crank lever 108 is provided with a boss 110 which is connected to a boss 111 pinned to a 55 shaft 112, journaled in bearings formed in the lasting head, by a screw 113 threaded for adjustment respectively in pivot pins in the bosses. The shaft 112 carries a sheave 114 which is connected by a screw 117 to the two 60 runs 115 and 116 of a wire arranged to work in the sheave groove. The run 115 passes over an idler 118 carried by the tacker bracket on the lasting head (Figs. 1 and 3), then over an idler 119 carried by a bracket 65 mounted on the machine frame (Figs. 1, 3

and 5), then under an idler 120 (Fig. 6) carried by a yoke supported by a bracket 121 bolted to a frame 83^a similar to the frame 83. The lower end of the run 115 then passes to a sheave 122 journaled in the bracket 121. 70 The lower ends of the runs 115 and 116 are connected to the sheave 122 by a screw 123 (Fig. 11). From the sheave 122 the run 116 passes under an idler 124 (Fig. 6), over an idler 125 (Fig. 5), and over an idler similar 75 to the idler 118 on the tacker bracket, back to the sheave 114. The feeler 107 is normally pressed toward the insole by a spring 126 (Fig. 3), one end of which is connected to a pin 127 secured to the machine frame, 80 and the other end of which is secured to a clamp 128 carried by the run 115.

The sheave 122 is connected, through a turn buckle rod 130, to a tiller 131 secured to a roll carrier 132 having a roll 133 arranged to engage the periphery of the continuously rotating drum 78. The roll carrier is supported in a carriage 134 mounted so that it may move longitudinally of the drum 78 upon horizontal rods 135 which are 85 carried in a yoke 136 projecting from the bearings for the shaft 78^a (Figs. 1 and 2). The roll is so mounted that it may be turned to vary the angle of the roll with relation to the direction of travel of the surface of the 90 drum. So long as the axis of the roll is parallel to the axis of the drum there will be no longitudinal movement of the carriage 134. When the roll is turned in either direction so that its axis is at an angle to the axis of the 95 drum, then the roll will tend to travel longitudinally of the drum and will move the carriage 134 in one direction or the other according to the direction in which the roll is turned, and the rate of movement in either 100 direction will depend upon the extent of the angular movement of the roll. The travel of the roll and carriage will cease as soon as the roll is returned to the position in which its axis is parallel to the axis of the drum. 105 The carriage 134 is connected by links 137 and 138 (Figs. 7, 8 and 11) to vertical arms 139 and 140 respectively secured to the rear ends of rock shafts 141 and 142 journaled in 110 bearings formed in the frame 83. The front 115 ends of the rock shafts 141 and 142 are each connected by a horizontal arm 143 to a turnbuckle rod 144 connected in turn to a lug 145 formed on the cam plate 100.

When the shoe is properly located for 120 the operation of the pincers the feeler 107 is in a neutral position, that is, a position in which the tiller 131 is held at right angles to the axis of the drum 78. Now then, when the operative presents a pre-selected 125 portion of the margin of the upper to the pincers the feeler 107 is lowered by the spring 126 if the insole adjacent the pre-selected margin of the upper inclines downwardly and to the front (Fig. 27). This 130

movement of the feeler rotates the sheave 114 in the direction of the arrow *a* (Fig. 27) and the sheave 122 in the direction of the arrow *b* (Fig. 11). Rotation of the 5 sheave 122 in the direction of the arrow *b* swings the tiller 131 in the direction of the arrow *c* (Fig. 11). The tiller thus turns the roll 133 so that its axis is at an angle to the axis of the drum and the roll will 10 travel longitudinally of the drum and will move the carriage 134 on the rods 135 in the direction of the arrow *d* (Fig. 11). Longitudinal movement of the carriage 134 in the direction of the arrow *d* (Fig. 11) 15 raises the cam plate 100 and turns the rolls 79 to slide the carriages 80 to the right (Fig. 7) which is in a direction to tilt, through the connections described, the shoe to the rear. The tilting of the shoe to the 20 rear elevates the feeler 107 which, through the wire over the sheaves 114 and 122, swings the tiller 131 in a direction opposite to that of the arrow *c* (Fig. 11). The movement of the carriage 134 also tends to swing 25 the tiller in a direction opposite to the arrow *c* since sheave 122 holds the end of the tiller from movement with the carriage. The reverse movement of the tiller, under the combined influence of the feeler as it is 30 returned to its normal position, and of the relative travel of the carriage and end of the tiller causes the roll and carriage to re-traverse the drum and return to their original or neutral position. This lowers the 35 cam plate 100 to straighten tiller 97 and stops the longitudinal movement of the carriage 80 and consequently the tilting of the shoe, as the feeler comes into neutral position.

40 As the carriage 80 is not returned to the position from which it started like the carriage 134, it is desirable that accidental overrunning of the carriage beyond the limits of its travel be prevented. To this 45 end the opposite ends of the cam plate 100 are provided with reversely arranged offsets 146 and 147 forming continuations of the cam groove 99. If for any reason the tiller 97 is not restored to a position where 50 the axes of the rolls 79 are parallel to the axis of the drum 78, when the roll 98 reaches the end of the groove 99, the roll 98 will be engaged by either the offset 146 or 147 and the tiller 97 will be turned to bring the 55 axes of the rolls 79 parallel to the axis of the drum 78.

60 If the portion of the insole engaged by the feeler inclines downwardly and to the rear then the feeler 107, through the connections described, swings the tiller 131 in the direction of the arrow *e* (Fig. 11). This causes the carriage to move longitudinally of the drum 78 and lower, through the connections described, the cam plate 100 to start 65 the carriage 80 moving in a direction to

70 actuate the mechanism for tilting the shoe to the front to bring the insole adjacent the presented portion of the upper into a plane perpendicular to the updraw movement of the pincers.

75 As hereinbefore stated, the machine of the drawings is provided with automatic mechanism for rocking the shoe to the right or left to coöperate with the mechanism for tilting the shoe to the front or rear and thus locate the insole adjacent the pre-selected portion of the margin of the upper in a plane perpendicular to the updraw movement of the pincers. The automatic mechanism for rocking the shoe to the right 80 or left is controlled by a feeler 148 formed on the end of a bell crank lever pivotally mounted upon the stud 109. The upper end of this bell crank lever is provided with a boss 149 which is adjustably connected to 85 a sleeve 150 on the shaft 112, by a threaded screw 151. The sleeve 150 carries a sheave 152 to which is secured a wire 153. The two runs of this wire pass over idlers similar to the idlers 118 on the tacker bracket, 90 then over idlers 154 (Fig. 5), then under idlers 155 and 156 (Fig. 6), finally being secured by a screw 157 to a sheave 158 rotatably mounted in a bracket 121^a on the frame 83^a. The sheave 158 is connected by 95 a turnbuckle rod 159 to a tiller 160 connected to a roll carrier 161 having a roll similar to the roll 133 engaged with the periphery of the continuously rotating drum 78. The roll carrier 161 is carried by a carriage 162 mounted to slide longitudinally of the drum 78 on the rods 135. The carriage 162 is connected by links 163 and 164 to vertical arms 165 and 166 (Figs. 9 and 10) respectively secured to the front ends 100 of rock shafts 167 and 168 journaled in the frame 83^a. Secured to the rear ends of each of the rock shafts 167 and 168 is a horizontal arm 170 which is connected by a vertical turnbuckle rod 171 to a lug 172 formed 110 on a vertically movable cam plate 173 similar in all respects to the cam plate 100.

When the operative presents a pre-selected portion of the margin of the upper to the pincers in such position that the plane 115 of the insole adjacent the pre-selected portion of the upper slants to the right or left, the feeler 148, through the wire 153 and connections described, either elevates or depresses the cam plate 173 depending whether 120 it is necessary to tip the shoe to the right or left in order to bring the insole adjacent the pre-selected portion of the upper in the proper working plane. The groove in the cam plate 173 engages a roll 174 on a tiller 125 175 arranged to operate two rolls 176 engaged with the periphery of the continuously rotating drum 78. The rolls are supported in a carriage 177 which is mounted to slide in the frame 83^a longitudinally of 130

the drum 78 in the same manner that the carriage 80 slides in the frame 83. When the cam plate 173 is elevated the rolls are turned to move the carriage 177 in one direction and when the cam plate is depressed the carriage 177 is moved in the other direction. The carriage 177 carries a rack 178 which is engaged by a segment 179 formed upon a bell crank lever 180 (Fig. 4) pivotally mounted on a stud 181 carried by a bracket 182 formed on the machine frame. The other end of the bell crank lever is formed as a segment 183 which meshes with a segment 184 formed on a walking beam 185 pivotally mounted on a rod 186 carried by the bracket 182. The walking beam 185 is connected by a pair of rods 187 to a walking beam 188 keyed to the shaft 50. Through the connections described the shoe 20 is automatically rocked to the right or left, the direction and extent of which is controlled by a mechanism operated by the feeler 148.

In order that the mechanism for tilting the shoe and thus correcting its position may be retained in an inactive and neutral position between successive operations of the shoe, mechanism is provided for nominally locking the correcting mechanism in a neutral position. This locking mechanism also serves to nominally retain the feelers in neutral position and to prevent tipping of the shoe by the operator or otherwise in feeding or moving it between successive operations of the correcting mechanism. As shown in Figs. 11, 12 and 14, this lock comprises a band brake 189 mounted to inclose the periphery of each of the sheaves 122 and 158. The band brake is constructed in two pieces 190 and 191 hinged together at 192. The free ends of the pieces 190 and 191 are respectively formed as lugs 193 and 194 which support a bolt 195. The pieces 190 and 191 are normally held pressed against the sheave by a spring 196 coiled about the shank of the bolt 195 and interposed between the lug 194 and a set of adjusting and locking nuts 197. With this construction the sheaves 122 and 158 are nominally locked by the brake bands. The hinged pieces of the brake band are separated to release the sheaves through a horizontal rock shaft 199 journaled in the brackets 121 and 121^a (Figs. 11 and 12), the opposite ends of which are provided with wedges 200 arranged to enter between the lugs 193 and 194, and separate the parts of the brakes against the tension of the springs 196 (Fig. 14). This shaft 199 is under the control of the operative. To this end one end of the shaft 199 is provided with an arm 201 which is connected to a lever 202, pivoted on a bracket 203 formed on the machine frame, by a link 204, one end of which is connected to the arm 201, and the other

end of which is connected to one end of the lever 202. The other end of the lever 202 is provided with a link 205, the lower end of which is connected to a floating rod 206 normally supported by a ledge formed on a link 207. The lower end of the link 207 is connected to the horizontal arm of a bell crank lever 208 (Fig. 2) pivoted on the machine frame. The vertical arm of the bell crank lever is connected by a horizontal link 209 to an arm 210 carried by a rock shaft 211 journaled in the machine frame. Intermediate its ends the rock shaft 211 is provided with a treadle lever 212 normally held in an inoperative position by a spring 213, one end of which is connected to the treadle and the other end of which is connected to the knee lever supporting bracket (Fig. 1).

After the operator places the shoe upon the jack the shoe is manipulated by rotating it or swinging it in a horizontal plane or by a combination of these movements until the insole adjacent to the portion of the upper desired to be operated upon is located at the working point. During this manipulation by the operator the shoe is held against tipping movement by the tipping and controlling mechanisms which are locked in neutral position by the locking mechanism above described. To permit the feelers to move upward under the pressure of the shoe sole when it is in position against the sole rest 2, the run of wire connected to the spring for each feeler is made in two sections joined by a yielding connection 198 (Figs. 1 and 3). This yielding connection enables the feelers to move upward from their neutral position even though the controlling mechanism with which they are connected is still locked. After the operator has positioned the shoe he depresses the treadle, thus releasing the controlling mechanism and feelers so that they may operate to correct the position of the shoe in accordance with the positions assumed by the feelers. As soon as the insole adjacent to the pre-selected portion of the upper is located in a plane at right angles to the updraw movement of the pincers, the lasting instrumentalities are thrown into operation to last the preselected portion of the upper.

In order to insure the proper positioning of the shoe before the lasting instrumentalities are thrown into operation, mechanism is provided, which for convenience may be termed indicating mechanism, which is brought into a certain position when the controlling mechanism is in neutral position and which so controls the throwing into operation of the lasting instrumentalities that these instrumentalities are not thrown into operation until the indicating mechanism is brought into a position which indicates that the controlling mechanism has acted and has corrected the position of the shoe.

As shown the indicating mechanism comprises horizontal arms 216 and 217 pivoted on a vertical pin 218 carried in a bracket 219 and connected by links 214 and 5 215 to the carriages 134 and 162 respectively. Each of the arms 216 and 217 is provided with a slot 220. These slots register when the carriages are stationary which, as heretofore described, occurs when the feelers are 10 in their neutral position. As soon as the registration of the slots indicates that the shoe is properly positioned, the lasting instrumentalities are operated by mechanism now to be described, to last the pre-selected 15 portion of the upper.

The lasting head driving shaft 22 is driven from the main driving shaft 79^b by a sprocket chain 221 which passes over a sprocket 222 carried by a sleeve 223 on the 20 shaft 22 and also over a sprocket 224 on the shaft 79^b. Normally the sleeve 223 rotates loosely on the shaft 22 but may be connected thereto to operate the lasting instrumentalities by a Horton clutch, indicated generally 25 at 225, (Fig. 3). This clutch is provided with the usual dog 226 (Fig. 16) arranged to be engaged by a yielding trip 227 to separate the sleeve and the shaft. The trip is carried by the vertical arm of a bell crank 30 lever 228 pivoted on the machine frame. The horizontal arm of the bell crank lever is connected to a vertical rod 229 slidably mounted in a guide lug 230 carried by the machine frame. The trip is normally held 35 in position to engage the dog by a spring 231 (Fig. 2) coiled around the rod 229 and interposed between a collar 232 secured to the rod and the lug 230. The lower end of the rod is slotted (Figs. 2 and 12) to loosely 40 embrace a pin 233 carried on one end of an arm 234 secured at its other end to a rock shaft 235 (Figs. 2, 4 and 12) pivoted in brackets 236 formed on the machine frame.

In the illustrated embodiment of the invention the clutch is tripped to operate the lasting instrumentalities as soon as the slots 220 register. To this end the shaft 79^b is provided with an eccentric 237 (Figs. 1 and 2) which oscillates, through the eccentric 50 strap and link connection 238, a lever 239 pivoted on the machine frame. The lever 239 is connected through a link 239^a to a bell crank lever 240 pivoted on a bracket 241 on the machine frame. The vertical arm of the bell crank lever is formed with a segmental slot 242 which embraces a block 243 (Figs. 2 and 12). This block carries the rod 206 and is provided with a chamber 244 which receives a plunger 245 formed on one end of 55 a rod 246, the other end of which is adjustably connected to a block 247 pivoted on an arm 248 depending from the rock shaft 235. Coiled around the rod 246 is a spring 249 interposed between the block 243 and a set of 60 adjusting and locking nuts 250 connecting

the rod 246 with the block 247. Through the connections described the block 243 is yieldingly connected to the rock shaft 235.

When the treadle 212 is elevated the block 243 is maintained in the bottom of the segmental slot 242 where it coincides with the pivotal movement of the bell crank lever 242, so that no movement is imparted to the rod 246. As soon, however, as the treadle is depressed, the block 243 is elevated in the 75 slot 242 by the link 207 and rod 206 and consequently the rod 246 is reciprocated by the rocking of the bell crank lever 240. Reciprocation of the rod 246 rocks the shaft 235 and causes an arm 251 depending from 80 one end of the rock shaft to move toward the slots 220 in the arms 216 and 217. If the shoe is being tipped, the lower end of the arm 251 strikes against the rear ends of the arms 216 and 217, the spring 249 at this 85 time yielding to prevent breakage. If, however, the slots 220 register indicating that the shoe is properly located for the lasting operation the lower end of the arm 251 enters the slots 220. This movement rocks the 90 shaft 235 which pulls down the rod 229 and trips the Horton clutch 225 to start the lasting instrumentalities.

In order to immediately relock the controlling mechanism and to restore the trip 95 227 of the Horton clutch to a position where it may engage the dog 226 after one revolution of the shaft 22 and stop the lasting instrumentalities, the lower end of the arm 248 is connected to a link 252 which is connected in turn to the link 207 by a pin and slot connection 253. With the construction described, the link 207 is pulled from beneath the pin 206 which supports the block 243 by the link 252 when the shaft 235 is 100 rocked, thereby permitting the block 243 to return to the bottom of the slot 242, the trip 227 to be restored to the influence of the spring 231, and the wedges 200 to be withdrawn to permit the band brakes to lock the 105 controlling mechanism in its neutral position. Then when the operative releases the treadle to the influence of its spring 213 the link 207 is reinserted beneath the pin 206 by a spring pressed pin 254 which is supported 110 in a lug 255 on the machine frame and arranged to continuously engage the front edge of the link 207.

In order to prevent accidental displacement of the shoe out of the position to which it has been placed by the operative in presenting the pre-selected portion of the upper to the pincers, the illustrated embodiment of the invention is provided with devices for locking the jack from rotation and also 120 from free movement in a horizontal plane as soon as the shaft 22 commences to operate. Referring now to Figs. 17 to 23 inclusive, these devices comprise a lock for preventing the pivotal movement of the frame 29, a lock 125 130

for preventing the pivotal movement of the frame 26, and a lock for preventing the rotation of the spindle 24.

In order to lock the frame 29 from movement the top of the vertical rod 30 is provided with a disk 256 having the opposite edges of its periphery beveled. Surrounding the disk 256 is a band wheel 257 carried by a frame 258 which is provided with a pin 259 loosely mounted in a socket 260 formed in the top of the rod 30. The band wheel 257 is formed in sections which are pivoted on a vertical pin 261 depending from the frame 258. The free ends of the band wheel are connected by a bolt 262 loosely mounted in lugs 263 formed in the sections of the wheel. The sections are normally forced toward each other so as to grip the disk 256 by a spring 264 coiled around the bolt 262 and interposed between one of the lugs 263 and a nut 265 threaded upon the bolt. The sections are forced apart against the tension of the spring 264 to release the disk 256 by a cam disk 266 keyed on a shaft 267, one end of which is journaled in the frame 258 and the other end of which is journaled in a frame 268 carried by the frame 26. The cam disk 266 is embraced by lugs 269 projecting from the sections of the band wheel 257, the construction being such that when the cam disk 266 is turned so that its wide portion engages the lugs 269, the disk 256 is released by the band wheel 257, and when the cam disk is turned so that its narrow portion is engaged by the lugs 269 the sections of the band wheel are restored to the influence of the spring 264.

To lock the spindle 24 from movement the frame 268 carries a band wheel 270, the sections of which are pivoted on a pin 271 and arranged to embrace a disk 272 splined to the spindle 24. The sections of the band wheel are normally spring pressed toward each other to grip the disk 272, but may be separated by a cam disk 273 carried by the shaft 267 and arranged to engage lugs 274 formed on the sections of the band wheel 270.

To lock the frame 26 from pivotal movement, or, stated in another way, to lock the toggle formed by the frames 26 and 29 from making or breaking movement, the shaft 267 is provided with a series of slots 275 which, when the shaft 267 is turned to cause the band wheels 257 and 270 to lock the disks 256 and 272, are engaged by a series of locking dogs 276. Each of these dogs is formed on the horizontal arm of a bell crank lever 277 pivoted on the frame 258, the vertical arm of which is engaged by a spring pressed pin 278 carried by the frame 258.

In order to turn the shaft 267 to lock the jack as soon as the driving shaft 22 commences to operate the shaft 267 carries a toothed disk 279, the teeth of which are

engaged by a rack 280 formed on the upper end of a vertical rod 281 mounted to slide in a chamber 282 carried by the frame 258 and through a slot 283 formed in the band wheel 257 and disk 256. The lower end of the rod 281 is carried by a projection from a hub 284 which is slidably mounted on the rod 30. This hub is provided with a groove 284^a which is engaged by rolls 285 carried by a yoke 286 keyed to a shaft 287 journaled in the jack frame. The shaft 287 is pivotally connected to a sleeve 288 which is splined to a rod 289 journaled in a yoke 290 carried by the plates 46 and 47 (Figs. 3 and 15). The rod 289 carries a pair of arms 291 each provided with a block 292 arranged to engage a groove 293 formed on a sleeve 294 on a rod 295 carried by the plates 46 and 47. A second groove 296 on the sleeve 294 is engaged by a block 297 carried upon one arm of a bell crank lever 298 pivoted on the plate 46. The other arm of the bell crank lever 298 carries a block 299 engaged by a groove 300 formed on a sleeve 301 on the shaft 50. This groove 300 also engages rolls 302 carried by a yoke 303 formed on a third arm 304 projecting from the rock shaft 19. As hereinbefore described the arm 20 carries a roll 305 engaged by the groove in the cam 21. Through the connections 95 described when the driving shaft 22 is thrown into operation the spindle 24 and the frames 26 and 29 are immediately locked so as to avoid displacement of the positioned shoe during the lasting operation, and are 100 then unlocked when the shaft 22 comes to rest to permit the operative to present another portion of the margin of the upper to pincers.

When no work is in the machine the controlling mechanism is locked in neutral position, the jack is unlocked to permit the rotation and free movement in a horizontal plane, the drum 78 is rotating without effect upon the traveling carriages, the eccentric 237 (Fig. 2) is idly reciprocating the lever 239, and the driving shaft for the lasting instrumentalities is at rest. After the operative places a shoe in position on the jack he rotates and moves the jack in a horizontal plane until the pre-selected portion of the upper to be operated on is presented at the working point. The operative then depresses the treadle. As soon as the treadle is depressed controlling mechanism and the feelers are freed to permit them to determine the proper operating position of the shoe. If the portion of the insole adjacent the pre-selected portion of the upper is not located in a plane perpendicular to the up-draw of the pincers this fact is ascertained by the feelers which throw into operation the mechanism for tipping the shoe to bring the portion of the insole adjacent the pre-selected portion of the upper into the proper 125 130

plane. As soon as the insole is brought into the proper plane the slots 220 (Fig. 11) register to permit the connections from the eccentric 237 to trip the clutch and drive the 5 shaft 22 to operate the lasting instrumentalities to last the pre-selected portion of the upper. Before the lasting instrumentalities commence to operate the controlling mechanism is locked and the jack is automatically locked from rotation and free 10 movement in a horizontal plane to prevent accidental displacement of the positioned shoe during the lasting operation. After one revolution of the shaft 22 the shaft is automatically stopped, the jack unlocked to 15 permit its rotation and free movement in a horizontal plane, and the disconnected treadle connections reconnected. Other pre-selected portions of the upper are successively presented at the working point in a similar manner until the shoe is lasted when the shoe is removed and another shoe placed upon the jack.

While the invention has been illustrated 25 and explained in its application to a lasting machine in which any pre-selected portion of the margin of the upper is presented at the working point and then the shoe automatically located so that the lasting instrumentalities may properly perform their 30 functions on such pre-selected portion and thereafter other pre-selected portions presented at the working point until the shoe is completely lasted, it will be understood that 35 some of the features of the invention may be embodied in machines for performing other operations especially in that type of machine in which there is a relative movement of the work and operating mechanism to 40 transfer the point of operation along the work. It will also be understood that the specific construction and arrangement of the parts is not material to the broader features of the invention and may be varied and 45 modified without departing from the invention.

During the course of the preceding description it has been convenient to employ various terms denoting direction of movement, but it is to be understood that those 50 terms are not expressive of any characteristic features of the invention but are used merely to facilitate explanation.

What is claimed as new is:—

55 1. A machine for operating on shoes, having, in combination, mechanism for operating on a shoe, a shoe supporting jack universally movable in a plane and rotatable in that plane to transfer the point of operation around the shoe, a feeler device acting on the sole of the shoe, and mechanism controlled by the feeler device for relatively tipping the operating mechanism and shoe to locate them in proper relation for the operation of the operating mechanism.

2. A machine for operating on shoes, having, in combination, mechanism for operating on a shoe, a shoe supporting jack universally movable in a plane and rotatable in that plane to transfer the point of operation around the shoe, a feeler acting on the sole of the shoe, and mechanism controlled by the feeler for relatively rocking the operating mechanism and shoe laterally to locate them in proper relation for the operation of the operating mechanism. 70

3. A machine for operating on shoes, having, in combination, mechanism for operating on a shoe, a shoe supporting jack universally movable in a plane and rotatable in that plane to transfer the point of operation around the shoe, a feeler acting on the sole of the shoe, and mechanism controlled by the feeler for relatively tilting the operating mechanism and shoe longitudinally to locate them in proper relation for the operation of the operating mechanism. 80

4. A machine for operating on shoes, having, in combination, mechanism for operating on a shoe and a shoe supporting jack relatively movable to transfer the point of operation around the shoe, mechanism for relatively rocking the operating mechanism and jack laterally to correct the position of the shoe with relation to the operating mechanism, and a single feeler engaging the shoe for controlling the rocking mechanism. 90

5. A machine for operating on shoes, having, in combination, means for operating on a shoe and a shoe supporting jack relatively movable to transfer the point of operation around the shoe, a feeler device engaging the shoe and mechanism controlled by the feeler device for tipping the jack to correct the position of the shoe with relation to the operating mechanism. 100

6. A machine for operating on shoes, having, in combination, mechanism for operating on a shoe, a shoe supporting jack, a feeler engaging the shoe, and mechanism controlled by the feeler for relatively tilting the operating mechanism and jack longitudinally to locate them in proper relation for the operation of the operating mechanism. 110

7. A machine for operating on shoes, having, in combination, mechanism for operating on a shoe, a shoe supporting jack, a pair of feelers engaging the shoe, and mechanism controlled by one feeler for imparting relative lateral rocking movements and by the other feeler for imparting relative longitudinal tilting movements to the operating mechanism and shoe to locate them in proper relation for the operation of the operating mechanism. 120

8. A machine for operating on shoes, having, in combination, mechanism for operating upon a shoe, mechanism for tipping the shoe, a feeler device constructed and ar- 130

- ranged to engage the shoe and connections between the feeler and tipping mechanism to determine the movements imparted to the shoe by the tipping mechanism.
- 5 9. A machine for operating on shoes, having, in combination, mechanism for operating on a shoe, mechanism for rocking the shoe, a feeler constructed and arranged to engage the shoe and connections between the feeler and rocking mechanism to determine the movements imparted to the shoe by the rocking mechanism.
- 10 10. A machine for operating on shoes, having, in combination, mechanism for operating on a shoe, mechanism for tilting the shoe, a feeler constructed and arranged to engage the shoe and connections between the feeler and tilting mechanism to determine the movements imparted to the shoe by the tilting mechanism.
- 15 11. A machine for operating on shoes, having, in combination, mechanism for operating on a shoe, a laterally swinging shoe supporting jack, mechanism for laterally 85
- 20 25 25 rocking the jack, and a feeler constructed and arranged to engage the shoe to determine the movements imparted to the shoe by the rocking mechanism.
- 30 12. A machine for operating on shoes, having, in combination, mechanism for operating on a shoe, a laterally swinging shoe supporting jack, mechanism for tilting the shoe, and a feeler constructed and arranged to engage the shoe to determine the movements 90
- 35 35 imparted to the shoe by the tilting mechanism.
- 40 13. A machine for operating on shoes, having, in combination, mechanism for operating on a shoe, a laterally swinging shoe supporting jack, mechanism for tipping the shoe, and feelers constructed and arranged to engage the shoe to determine the movements 95
- 45 50 50 imparted to the shoe by the tipping mechanism.
- 55 14. A machine for operating on shoes, having, in combination, mechanism for operating on a shoe, a shoe supporting jack, means for relatively tipping the operating mechanism and shoe to locate them in proper relation for the operation of the operating mechanism, and means for indicating when the operating mechanism and shoe are located in proper relation for the operation of the operating mechanism.
- 60 15. A machine for operating on shoes, having, in combination, automatically operating pincers, a shoe supporting jack movable to permit pre-selected portions of the upper to be successively presented to the pincers, mechanism for tipping the shoe to bring the insole adjacent the presented portion of the upper into a plane perpendicular to the updraw movement of the pincers, and a feeler device constructed and arranged to engage the shoe to determine the 100
- 65 65 direction and extent of the movements imparted to the shoe by the tipping mechanism.
16. A machine for operating on shoes, having, in combination, an operating tool, a horizontal shaft having its axis passing through the point of operation of the tool, a depending frame carried by the shaft, a curved slideway formed on the frame with its center of curvature coinciding with the point of operation of the tool, and a shoe supporting jack slidably mounted in the slideway.
17. A machine for operating on shoes, having, in combination, an operating tool, a horizontal shaft having its axis passing 70
18. A machine for operating on shoes, having, in combination, an operating tool, a horizontal shaft having its axis passing 80
19. A machine for operating on shoes, having, in combination, means for operating on a shoe, a shoe supporting jack, correcting mechanism for tipping the jack, mechanism for controlling the correcting mechanism, and a feeler device constructed and arranged to engage the shoe to govern the controlling 105
20. A machine for operating on shoes, having, in combination, means for operating on a shoe, a shoe supporting jack, mechanism for tipping the jack to bring the portion of the sole surface adjacent the working point into substantially the same plane, and a feeler device constructed and arranged to engage the shoe to determine the direction and extent of the movements imparted to the 110
21. A machine for operating on shoes, having, in combination, mechanism for operating on a shoe, a shoe supporting jack, mechanism for tipping the shoe to locate the 115
22. A machine for operating on shoes, 120
23. A machine for operating on shoes, having, in combination, mechanism for operating on a shoe, a shoe supporting jack, mechanism for tipping the shoe to bring the portion of the sole surface adjacent the working point into substantially the same plane, and a treadle for successively throwing the tipping and operating mechanisms into operation.
24. A machine for operating on shoes, 125

- having, in combination, normally inoperative mechanism for operating on a shoe, a shoe supporting jack, means for relatively tipping the inoperative operating mechanism and shoe to locate them in proper relation for the operation of the operating mechanism, means for indicating when the operating mechanism and shoe are located in proper relation for the operation of the operating mechanism, and means controlled by the indicating means for throwing the operating mechanism into operation. 70
23. A machine for operating on shoes, having, in combination, normally inoperative mechanism for operating on a shoe, a shoe supporting jack movable to permit the operative to present a pre-selected portion of the shoe to the operating mechanism, means for relatively tipping the operating mechanism, and shoe to locate them in proper relation for the operation of the operating mechanism, means for automatically throwing the operating mechanism into operation when the operating mechanism and shoe are brought into the proper relation for the operation of the operating mechanism, and means for locking the jack from movement when the operating mechanism is thrown into operation. 75
24. A machine for operating on shoes, having, in combination, normally inoperative mechanism for operating on a shoe, power operated mechanism for throwing the operating mechanism into operation, and means controlled by the shoe as it is moved into a position for the operation of the operating mechanism for preventing the power operated mechanism from throwing the operating mechanism into operation until the shoe and operating mechanism are brought into a predetermined relation. 80
25. A machine for operating on shoes, having, in combination, an operating tool, means for operating said tool, a shoe supporting jack universally movable in a single plane and rotatable in that plane to permit the point of operation of the tool to be transferred around the shoe, and means for locking the jack from movement of either translation or rotation during the operation of the operating tool. 85
26. A machine for operating on shoes, having, in combination, means for operating on a shoe, and a shoe supporting jack relatively movable to transfer the point of operation around the shoe, feelers engaging the shoe, mechanism controlled by the feelers for relatively moving the operating mechanism and shoe to locate them in proper relation for the operation of the operating mechanism, and means for locking the controlled mechanism in position to permit the shoe to be removed from the machine without effect upon the mechanism controlled by the feelers. 90
27. A lasting machine, having, in combination, mechanism for lasting an assembled shoe including a wire-reel-spring-tension-releasing rod, and mechanism operated wholly by the machine for automatically actuating the rod. 95
28. A machine for operating on shoes, having, in combination, mechanism for operating on a shoe, a rotary drum, a roll constructed and arranged to engage the drum, a feeler engaging the shoe, connections for holding the roll with its axis parallel to the axis of the drum when the feeler is in neutral position and for turning the roll at an angle when the feeler is moved out of a neutral position, and mechanism actuated by the relative lateral travel of the roll tending to restore the feeler to neutral position and through which the position of the shoe with relation to the operating mechanism is corrected. 100
29. A machine for operating on shoes, having, in combination, mechanism for operating on a shoe, a shoe supporting jack, a rotary drum, a roll engaging the drum, connections through which the relative lateral travel of the roll corrects the relative position of the jack and operating mechanism, and a feeler engaging the shoe and connections for controlling the angle of the roll. 105
30. A machine for operating on shoes, having, in combination, mechanism for operating on a shoe, a shoe supporting jack and a feeler relatively movable to transfer the feeler along the shoe, a rotary drum, a roll engaging the drum, connections through which the angle of the roll is controlled by the feeler, and connections through which the relative lateral travel of the roll corrects the relative position of the shoe and operating mechanism in accordance with the shape of that portion of the shoe with which the feeler has engagement. 110
31. A machine for operating on shoes, having, in combination, mechanism for operating on a shoe, a shoe supporting jack, a feeler for engaging the shoe, and mechanism rendered active upon the movement of the feeler out of neutral position for continuously correcting the relative position of the shoe and operating mechanism while the feeler remains out of neutral position. 115
32. A machine for operating on shoes, having, in combination, devices for operating on a shoe, a shoe supporting jack, mechanism for relatively actuating the operating devices and shoe to locate them in proper relation for the operation of the operating devices, a feeler engaging the shoe movable into and out of neutral position, and mechanism connected with the feeler to continuously modify the action of the first named mechanism so long as the feeler is out of neutral position. 120
33. A machine for operating on shoes, having, in combination, devices for operat- 125

ing on a shoe, a shoe supporting jack, mechanism for relatively actuating the operating devices and shoe to locate them in proper relation for the operation of the operating mechanism including the rotary drum and a carriage mounted to move parallel with the axis of the drum, a roll in the carriage rotating on the drum, a feeler engaging the shoe and connections for varying the angle 10 of the roll, and an auxiliary means operating automatically and independently of the feeler for restoring the turned roll to a position in which its axis is parallel to the drum.

34. A lasting machine, having, in combination, lasting pincers, operating means therefor, shoe supporting means constructed and arranged to permit the lowering of the shoe on the supporting means from the working point, the changing of its angular 20 relation to said point and its return to working position, and automatic means for stopping the operation of the pincers after each cycle of movements thereof to allow the described manipulation of the shoe supporting 25 means between cycles of movements of the lasting pincers.

35. A machine for operating on shoes having in combination means for operating on a shoe, a feeler engaging the shoe, mechanism 30 controlled by the feeler for relatively moving the operating means and shoe to locate them in proper relation for the operation of the operating means and means for locking the controlled mechanism between successive operations.

36. A machine for operating on shoes having in combination means for operating on a shoe, a feeler engaging the shoe, mechanism controlled by the feeler for relatively 40 moving the operating means and shoe to locate them in proper relation for the operation of the operating means and means for normally locking and intermittently releasing the controlling mechanism.

45. 37. A machine, having, in combination, operating means, a plurality of feelers arranged to engage the same face of the work adjacent to the point of operation of the operating means, and mechanism controlled 50 by the feelers for relatively tipping the work and operating means about two axes to position said face with relation to the operating means.

38. A machine, having, in combination, 55 operating means, a work support universally movable in a plane to permit the operator to present a preselected portion of the work to the operating means, feelers arranged to engage the surface of the work 60 adjacent to the operating means, and mechanism controlled by the feelers for tipping the work to position said surface with relation to the operating means.

39. A machine, having, in combination, 65 operating means, a support therefor, a work

support, one of said supports being universally movable in a plane, a feeler device to act on the work, and mechanism controlled by the feeler for relatively tipping the operating means and work to bring them into 70 proper relation for the operation of the operating means on the work.

40. A machine, having, in combination, operating means, a work support, feelers arranged to engage the work adjacent to the point of operation of the operating means, and mechanism controlled by the feelers for tipping the work in two directions to properly position the surface engaged by the feelers at the point of operation. 80

41. A machine, having, in combination, operating means, a pair of feelers for engaging the work, and mechanism controlled by one feeler for imparting relative lateral rocking movements and by the other feeler 85 for imparting relative longitudinal tilting movements to the operating means and work to locate them in proper relation for the operation of the operating means.

42. A machine, having, in combination, 90 operating means, mechanism for tipping the work, a feeler arranged to engage the work, and connections between the feeler and tipping mechanism to determine the movements imparted to the work by the tipping 95 mechanism.

43. A machine, having, in combination, operating means, automatically acting mechanism for relatively tipping the operating 100 means and work to locate them in proper relation for the operation of the operating means, and means for indicating when the operating means and work are located in proper relation for the operation of the operating means. 105

44. A machine, having, in combination, operating means, a work support, mechanism for tipping the work about two axes to bring the surface of the work adjacent 110 to the working point into a given plane, and feelers for engaging the surface of the work adjacent to the working point to determine the extent and direction of the movements imparted to the work by the tipping mechanism. 115

45. A machine, having, in combination, operating means, correcting mechanism under the control of the operator for positioning the work with relation to the operating means, and driving mechanism for the 120 operating means controlled by the correcting mechanism.

46. A machine, having, in combination, normally inactive operating means, a work support, means for relatively tipping the 125 operating means and work to locate them in proper relation for the operation of the operating means, means for indicating when the operating means and work are located in proper relation, and means controlled by 130

the indicating means for throwing the operating means into operation.

47. A machine, having, in combination, normally inactive operating means, a work support movable to permit the operator to present a preselected portion of the work to the operating means, means for relatively tipping the operating means and work to locate them in proper relation for the operation of the operating means, means for automatically throwing the operating means into operation when the operating means and work are brought into proper relation, and means for locking the work support from movement when the operating means is thrown into operation.

48. A machine, having, in combination, normally inactive operating means, actuating mechanism therefor, mechanism for automatically throwing in the actuating mechanism, and means controlled by the work as it is moved into position for the operation of the operating means for preventing the throwing in of the actuating mechanism until the work and operating means are brought into a predetermined relation.

49. A machine, having, in combination, a rotary drum, a roll carriage mounted for movement lengthwise of the drum, a roll 30 in the carriage engaging the drum, a second roll carriage, a roll therein engaging the drum, a feeler, and connections for turning the second roll at an angle to the drum, connections between the second carriage and 35 first roll for turning said roll at an angle to the drum, and a part connected to be moved by the travel of the first carriage.

50. A machine, having, in combination, two roll carriages, a roll in each carriage, 40 a traveling drum engaged by each roll, a feeler and connections for turning one roll at an angle to the direction of travel of the drum surface engaged thereby, connections between the carriage for this roll and 45 the other roll for controlling the angle of the latter roll, and a movable part connected to be moved by the movement of the carriage for the latter roll.

ERASTUS E. WINKLEY.
